FIG 4

FIG 5

FIG 6

FIG 7

FIG 8

FIG 9

FIG 10

FIG. 1 is a perspective view of one embodiment of a swinging gate constructed in accordance with my design;

FIG. 2 is a front elevational view thereof as shown in FIG. 1;

FIG. 3 is a rear elevational view thereof as shown in FIG. 1;

FIG. 4 is a top plan view thereof as shown in FIG. 1;

FIG. 5 is a right elevational view thereof as shown in FIG. 1;

FIG. 6 is a left elevational view thereof as shown in FIG. 1;

FIG. 7 is a perspective view of the second embodiment of the swinging gate of the present invention;

FIG. 8 is a front elevational view thereof as shown in FIG. 7;

FIG. 9 is a top plan view thereof as shown in FIG. 7; and

FIG. 10 is a right elevational view thereof as shown in FIG. 7.

The broken line disclosure of a ground support in FIG. 1 is for illustrative purposes only.

The rear elevational view and left elevational view of the second embodiment of the swinging gate embody the same configuration as shown in the front elevational view in FIG. 8 and the right elevational view in FIG. 10, respectively.

I claim:

The ornamental design for a swinging gate, as shown and described.
